UNITED STATES PATENT OFFICE.

LEONARD O. PULLEN, OF AUGUSTA, MAINE, ASSIGNOR OF ONE-HALF TO
THOMAS J. LYNCH, OF AUGUSTA, MAINE.

TROLLEY.

SPECIFICATION forming part of Letters Patent No. 781,359, dated January 31, 1905.

Application filed March 26, 1904. Serial No. 200,159.

To all whom it may concern:

Be it known that I, LEONARD O. PULLEN, a citizen of the United States, residing at Augusta, in the county of Kennebec and State 5 of Maine, have invented certain new and useful Improvements in Trolleys, of which the following is a specification.

My invention relates to trolley poles and stands for electric cars, and has for its object 10 the provision of means for catching the trolley-pole should the wheel leave the wire or should the rope that holds it in an inoperative position break. In the trolleys as at present constructed when the wheel leaves the wire 15 they fly upward, endangering the guy-wires, &c., until the car is stopped; and my invention is intended to prevent the pole flying up in such emergencies, so that the overhead structures are not damaged and the necessity for 20 stopping the car averted.

The construction and advantages of my invention will fully appear hereinafter and by reference to the accompanying drawing, which shows a trolley stand and pole, partly in section, constructed in accordance with my invention.

1 represents a suitable base-plate secured to the roof of the car and having a circular groove 2 formed therein, in which rest antifriction 30 rollers or balls 3.

4 represents the base of the trolley-stand, which is revolvably mounted on base-plate 1 by means of bolt 5, which is placed in the center of circular groove 2.

35 6 represents the pole-support, secured to base 4, on which is pivotally mounted, by means of bolt 7, the pole-socket 8, made of two parts held together by bolts or screws, so as to admit of their being readily dismembered.

40 9 represents a segmental ratchet formed on the top and rear of support 6, and 10 a pawl slidably mounted in socket 11, formed by making a channel in each of the two parts of pole-socket 8.

45 12 represents a spring to actuate pawl 10, mounted on reduced portion 13 of the pawl and bearing between a shoulder 14 on one of

the parts of the socket and a nut 15, mounted on screw-threads 16 on said reduced portion 13, the purpose of nut 15 being to permit the 50 tension of spring 12 to be regulated as desired.

17 represents the trolley-pole, adapted to seat in socket 8 and held therein by means of straps 18, secured to each part of said socket and held together by means of bolts 19. 55

20 represents the trolley-head, pivoted in the other end of the trolley-pole, having a trolley-wheel 21 journaled in its outer end, and 22 the rope for operating the pole. The pole is made hollow or tubular to receive a rod 23, having 60 one end pivotally secured to trolley-head 20 and its other end adapted to enter longitudinal bore 24 in pawl 10.

25 represents a set-screw for holding rod 23 in bore 24, and 26 a hole formed by registering notches in the two parts of socket 8 to permit the set-screw to be operated from the outside of the socket. 65

The front of support 6 is extended, as shown at 27, and has slidably mounted thereon a 70 block 28.

29 represents springs secured to block 28 and having their free ends secured to curved blocks 30, secured to the sides of socket 8. The tension of springs 29 is adjustable by 75 means of a screw-rod 31, journaled in the shoulder 32 on the extended end 27 of support 6 and having its screw-threaded portion intermembering with a screw-threaded bore in said block. 80

In operation the trolley-pole may be adjusted by means of rope 22, a slight pull being necessary to overcome the tension of spring 12, and as the tension of springs 29 is greater than that of spring 12 the trolley-head when 85 in position against the line-wire will be depressed, so as to draw pawl 10 out of engagement with the teeth of ratchet 9; but should the trolley-head jump away from the line-wire the spring 12 will instantly push the pawl 90 downward into engagement with said ratchet 9. The same thing would occur if when the pole is held down out of engagement with the wire the rope should break. In fact, my in-

vention may be used to hold the trolley-pole in an inoperative position by pulling the pole down and suddenly letting go of the rope.

Having thus described my invention, what I claim is—

1. In a trolley, a trolley-stand having a segmental ratchet, a pole-socket pivotally mounted on said stand, a pawl slidably mounted in said socket, a spring to actuate said pawl, means to regulate the tension of said spring, the pole secured in said socket, the trolley-head pivotally mounted on the free end of said pole, and means to connect said pawl and head, substantially as shown and described.
- 15 2. In a trolley, a trolley-stand having a segmental ratchet, a pole-socket pivotally mounted on said stand, a pawl slidably mounted in said socket having a reduced portion, screw-threads on said reduced portion, a nut engaging said screw-threads, a spring mounted on said reduced portion and bearing between said nut and shoulder on the socket, the pole secured in the socket, the trolley-head pivotally mounted on the free end of the trolley-pole, and means to connect said pawl and head, substantially as shown and described.
- 25 3. In a trolley, a trolley-stand having a segmental ratchet, a pole-socket pivotally mounted on said stand, a pawl slidably mounted in

30 said socket having a reduced portion and provided with a bore, a spring to actuate said pawl, means to regulate the tension of said spring, the pole secured in said socket, the trolley-head pivotally mounted on the free end of said pole, and a rod secured to said trolley- 35 head and in the bore of said pawl, substantially as shown and described.

4. In a trolley, a trolley-stand having a segmental ratchet, a pole-socket pivotally mounted on said stand, a pawl slidably mounted in 40 said socket having a reduced portion and provided with a bore, screw-threads on said reduced portion, a nut engaging said screw-threads, a spring mounted on said reduced portion and bearing between said nut and a 45 shoulder on the socket, a tubular pole secured in the socket, the trolley-head pivotally secured in the free end of the pole, a rod pivotally secured to the trolley-head and adapted to be inserted in the bore in the pawl, and a 50 set-screw to hold the rod in said pawl, substantially as shown and described.

In testimony whereof I hereto affix my signature in the presence of two witnesses.

LEONARD O. PULLEN.
